Des. 120

Chas W. Warnick & Frederick Leibrandt. Philadelphia Pa.
Letters Patent (Design No. 120) dated 8th May 1847.

The schedule referred to in these Letters Patent and making part of the same.

To all whom it may concern:
Be it known that we Chas W. Warnick and Frederick Leibrandt trading under the firm of Chas W. Warnick & Co. of the City of Philadelphia, State of Pennsylvania, have invented or produced a cast iron ornamental frame, to be used on a Summer oven, styled a Gas oven, and we do hereby declare that the annexed drawing is a full and exact description of the same.

You pretences claim to be the original inventors, or producers of the Design, and ornamental part of said frame.

March 15th 1847.
